United States Patent Office

Des. 218,353

Patented Aug. 11, 1970

218,353

SERVING TRAY

Thomas H. Eckdahl, Minneapolis, Minn., assignor to
Plastics, Inc., St. Paul, Minn., a corporation of
Delaware

Filed June 6, 1969, Ser. No. 17,551

Term of patent 14 years

Int. Cl. D7—99

U.S. Cl. D44—10

FIG. 1

FIG. 2

FIG. 3

FIG. 4

FIG. 5

FIG. 1 is a top plan view of a serving tray showing my new design.

FIG. 2 is a front elevational edge view thereof.

FIG. 3 is a rear elevational edge view.

FIG. 4 is a sectional view on the line 4—4 of FIG. 1.

FIG. 5 is a bottom plan view thereof.

I claim:

The ornamental design for a serving tray, as shown.
